UNITED STATES PATENT OFFICE.

LAWRENCE FRANK, OF GALVESTON, TEXAS.

PROPELLER-PITCHOMETER.

1,140,260.

Specification of Letters Patent. Patented May 18, 1915.

Application filed October 21, 1914. Serial No. 867,882.

To all whom it may concern:

Be it known that I, LAWRENCE FRANK, citizen of the United States, residing at Galveston, in the county of Galveston and State of Texas, have invented certain new and useful Improvements in Propeller-Pitchometers; and I do hereby declare the following to be a full, clear, and exact description of the invention, such as will enable others skilled in the art to which it appertains to make and use the same.

This invention relates to measuring instruments, and more especially to pitchometers; and the object of the same is to produce a machine for measuring the pitch of the blades of propellers.

To this end the invention consists in the details of construction hereinafter more fully described and claimed, and as shown in the drawings wherein—

Figure 1 is a plan view of one form of this instrument mounted upon a propeller (the latter being shown in dotted lines), ready for use excepting that the arms of the pitchometer are turned a little to one side from a position truly overlying two of the blades or flukes of the propeller; and Fig. 2 is a left side elevation of Fig. 1 with the instrument turned so that its arms truly coincide with two of the propeller blades. Fig. 3 is a central vertical section through the instrument alone, taken on the line 3—3 of Fig. 1. Fig. 4 is a plan view of another form of the gage plate comprising but a single arm, and Fig. 5 is a sectional detail on the line 5—5 of Fig. 4. Fig. 6 is a perspective view of another form of the instrument comprising but a single arm which itself is adjustably supported on the hub member.

Broadly speaking, the instrument comprises a hub member, a plate made in one or two arms, and a series of set screws. The hub member comprises a centering pin 1 which is adapted to fit closely into the bore in the hub of the propeller indicated at P, a lower block 2 preferably rectangular in contour and integral with the upper end of the pin 1, the upper extremity of the block being beveled as at 3, an upper block 4 also preferably rectangular in contour and of the same size as the lower block and with its lower extremity beveled as at 5, a bolt 6 which extends centrally through holes in the two blocks and throughout the length of the pin 1 and has its head 7 disposed at the lower

end of the latter, a jam-nut 8 on the upper threaded end of the bolt 6, and a guide-plate having one leaf 9 lying along the longer side of the lower block 2 and the shorter side of the upper block 4, a head leaf 10 overlying the flat upper end of the upper block 4 and pierced with a hole through which the bolt 6 projects, and a lip 11 hanging over the longer face of the upper block 4—all as best seen in Figs. 2 and 3. Ordinarily the propeller will be laid upon a suitable support, such as a pair of horses not shown, and the pin 1 passes down through the bore of its hub whereby the hub member above described, and the parts carried by it, will be supported above the propeller and may be rotated from time to time. The head 7 of the bolt 6 will therefore be smaller than the hole in the propeller hub and smaller than the pin 1 so that it may pass through said hole; and, while I prefer to make the blocks 2 and 4 square in contour, they may be of any other appropriate shape. The leaf 9 overlying corresponding faces of the two blocks causes them to approach each other in such manner when the thumb-nut is turned that their beveled faces 3 and 5 remain ever in parallelism, and therefore any flat member which is placed between these faces will be clamped thereby when the thumb-nut 8 is set up sufficiently.

The second member of this instrument is a plate of proper metal and of sufficient thickness to make it quite rigid. In the first three views of the drawings this plate is shown as having two arms 15 and 16 which are of corresponding and similar construction and are connected integrally by an interposed shank 17 pierced with a hole 18 through which the bolt 6 may pass, and in the other views the plate is composed of but a single arm which corresponds with one of the two arms in the double-armed construction, and need not therefore be elaborately described. When the double-armed plate is used, its arms will lie approximately or exactly in a single plane which is the plane of the shank 17, and the latter will be clamped between the beveled faces 3 and 5 of the hub member so as to hold it oblique to a plane at right angles to the axis of the pin 1. When this plate member has but a single arm as shown in the remaining views, it needs some means to support it by the hub member. In Fig. 4 it is projected at one edge into a shank 19 which has the hole 18

for the passage of the bolt 6, the same as in the two-armed plate; and it will be clear that by reversing this plate so that its upper face is lowermost, its obliqueness may be 5 changed and it may be used on a propeller blade inclined in the opposite direction. The means for supporting the single arm shown in Fig. 6 is described below.

Through each arm are bored holes 20 10 which stand on lines strictly at right angles to the plane of the arm, and through each hole is passed a set screw 21, preferably having a flattened head 22 possibly provided with a number to match the same 15 number stamped on the plate adjacent the hole 20. Onto the body of the set screw runs a nut 23 which may fit with considerable friction thereon or may be held thereon against rotation by a jam nut 24, and the 20 lower or working end of the set screw is preferably reduced as shown at 25. There will be as many holes and set screws as desired, and they are widely scattered throughout the area covered by the arm, although I 25 consider it essential that a row of the holes shall be disposed around the edge of this arm in any event, and quite a number near its center for purposes yet to appear.

In the form of my invention illustrated in 30 Fig. 6, the hub member has the same pin 30, a single block 31 provided with a series of transverse holes 32 passing through it at different elevations and in different directions, and no guide-plate or jam screw. The 35 plate has a single arm 33 pierced with holes 20 for the set screws 21. The connections between the block and arm, however, are different. Herein the shank is in the form of a bolt 34 passing through one of the holes 32 40 and held by a nut 35 on each side of the block 31, and the outer end of the bolt passes under a clip 36 secured upon the arm in any suitable way as by rivets 37, and is held in said clip by a set screw 38. The body 45 of this bolt 34 is round, and where it passes under the clip the latter is rounded. The result is that when the set screw is loosened the clip, and with it the entire arm and the 50 set screws carried by such arm, may be rocked over the outer end of the bolt 34 to adjust the plane of the plate with reference to the axial line of the pin 30; after which the set screw 38 can be set up tight to hold the plate or arm in such adjustment. To 55 this extent this form of my invention differs from those illustrated in the other views, because it can be used on the blades of propellers whose pitch or angles vary, and can be accommodated to such varying pitch by 60 means of the set screw 38.

The use of this device is as follows: The propeller P is laid on a suitable support, and the pin 1 or 30 is passed through the hole in the hub. If it be a right-hand propeller, 65 the proper arm of the plate shown in Figs.

1, 2 and 3 is employed, or the single arm shown in Fig. 4 may be used by setting it right side up in the hub member and clamping it between the blocks 2 and 4. Obviously the arm shown in Fig. 6 can be used 70 with either a right-hand or a left-hand propeller, because the arm can be set by means of the set screw 38. Most propellers when first cast are rather rough, and their faces have to be trued by suitable machining. In 75 order to ascertain when the grinding off of said rough material is sufficient, this testing device or pitchometer is brought into place. As the workman treats each blade or fluke of the propeller, the arm of the instrument is turned aside as indicated partly by the dotted position of the propeller in Fig. 1, so as to give him access to the face of the propeller blade upon which he is working; and from time to time he swings this arm back 80 into position directly above the propeller blade so that the tips 25 of the set screws contact therewith. By this means he can readily ascertain which set screw contacts 85 first, and thereby he is informed what part 90 of the face of the propeller blade must be treated or ground off to a greater extent and until all of the tips 25 contact simultaneously. If it is the intention to give the propeller blade a greater pitch, the set screws 95 will be adjusted accordingly by means of their set nuts 23 and 24. If the propeller be one which is to rotate in the opposite direction, he will use the other arm of the instrument shown in Figs. 1, 2 and 3, or he 100 may remove the plate shown in Fig. 4 from its hub member and reverse it, passing the hole 18 over the bolt 6 and clamping it between the beveled faces of the two blocks as before, and withdrawing the set screws 21 105 and inserting them through the holes 24 from the opposite direction until their nuts 23 contact with the then upper face of the arm. The single-arm type of blade shown in Fig. 6 obviously may not be thus reversed 110 because the clip or bracket 36 will interfere; but the especial function of this form of my invention is to provide a single instrument which may be used on different propellers 115 whose blades have a variety of pitches or inclinations, whereas the adjustability of the several set screws in any form of my instrument is obviously for the purpose for varying the pitch or inclination at different points on the face of any propeller-blade. 120

Thus is produced a pitchometer for propellers by means of which the objects above described may easily be carried out. Also the instrument is useful for centering the screws so as to secure true adjustment of the 125 propeller on its shaft. The instrument is further useful for old propellers where it is supposed that they have been strained or injured, and in some cases it is quite possible to use the instrument for taking the 130

pitch of existing propeller blades so as to add a new one which may have become broken off or injured beyond repair. The size and proportion of parts, as well as their material and the exact details of construction, are matters of no moment.

What is claimed as new is:

1. The herein described pitchometer for propeller blades, the same comprising a hub member having a pin adapted to enter the hole in the propeller hub, a plate having a series of threaded holes through it, screws through said holes with their tips adapted to contact with the face of the propeller blade, a shank connected with the plate, and adjustable connections between the shank and hub member whereby the position of the plate with respect to the blade may be changed.

2. The herein described pitchometer for propeller blades, the same comprising a hub member having a pin adapted to enter the hole in the propeller hub, a plate having a series of pendant elements adapted to contact with the face of the propeller blade, a support for the plate, and movable threaded connections between the support and hub member whereby the position of the plate with respect to said member is rendered adjustable.

3. In an instrument of the class described, the combination with a hub member comprising a lower block with a beveled upper face, a pin depending from said block, an upper block with a beveled lower face, and means for drawing said blocks toward each other; of a plate having a shank adapted to be clamped between said beveled faces and a series of holes through its body, and set screws through said holes, for the purpose set forth.

4. In an instrument of the class described, the combination with a hub member consisting of a lower block having a beveled upper face and a tubular pin projecting from its lower face, an upper block having a beveled lower face and a hole through its body, a bolt extending through said hole and through the lower block and pin and having a reduced head at the lower end of said pin, and a jam nut on the upper end of said bolt; of a plate having a shank adapted to be clamped between said beveled faces and a series of holes through its body, and set screws through said holes, for the purpose set forth.

5. In an instrument of the class described, the combination with a hub member consisting of a lower block having a beveled upper face and a tubular pin projecting from its lower face, an upper block having a beveled lower face and a hole through its body, a bolt extending through said hole and through the lower block and pin and having a reduced head at the lower end of

said pin, and a jam nut on the upper end of said bolt; of a plate conforming in contour with the propeller blade and having an offset shank pierced with a hole and adapted to pass over said bolt, and a series of adjustable elements on said plate adapted to contact with the face of the propeller blade.

6. In an instrument of the class described, the combination with a hub member comprising a lower block of rectangular contour having its upper face beveled, a hole through its body, and a tubular pin depending rigidly from its lower face, an upper block of corresponding contour having a hole through its body and its lower face beveled, a guide plate having a leaf lying along one exterior face of both blocks, a second leaf overlying the upper block and pierced with a hole, and a lip depending alongside that face of the upper block which is remote from the first-named face, a bolt extending through the pin and both blocks and the upper leaf of the guide-plate, and a jam nut on the upper end of the bolt; of a plate having a shank pierced with a hole adapted to receive said bolt when the shank stands between the beveled faces of the blocks, and a series of adjustable pendant members on said plate adapted to contact with the upper face of the propeller blade, for the purpose set forth.

7. In an instrument of the class described, the combination with a hub member comprising a lower block of rectangular contour having its upper face beveled and a pin depending rigidly from its lower face, an upper block of corresponding contour having its lower face beveled, a guide plate having a leaf lying along one exterior face of both blocks, a second leaf overlying the upper block, and a lip depending alongside that face of the upper block which is remote from the first-named face, and means for drawing said blocks toward each other; of a plate having a shank standing between the beveled faces of the blocks, and a series of adjustable pendant members on said plate adapted to contact with the upper face of the propeller blade, for the purpose set forth.

8. In an instrument of the class described, the combination with a hub member comprising a lower block of rectangular contour having its upper face beveled and a pin depending rigidly from its lower face, an upper block of corresponding contour having its lower face beveled, a guide plate having a leaf lying along one exterior face of both blocks, a second leaf overlying the upper block, and a lip depending alongside that face of the upper block which is remote from the first-named face, and means for drawing said blocks toward each other; of a plate comprising two arms and an inter-

posed shank all standing in a single plane and the arms pierced with a series of threaded holes, the shank adapted to be clamped between the beveled faces of said blocks, a series of screws adapted to pass through the holes in either arm from either direction, and nuts on said screws.

In testimony whereof I affix my signature in presence of two witnesses.

LAWRENCE FRANK.
